FOREIGN PATENT DOCUMENTS

WO ..... WO-9321856 A1 * 11/1993 ..... A61C 17/02

Primary Examiner — Sheryl Lane

Assistant Examiner — Calvin E Vansant

(57) **CLAIM**

The ornamental design for a water flosser, as shown and described.

DESCRIPTION

FIG. 1 is a first perspective view of a first component of a water flosser showing my new design;

FIG. 2 is a second perspective view thereof;

FIG. 3 is a third perspective view thereof;

FIG. 4 is a fourth perspective view thereof;

FIG. 5 is a first perspective view of a second component of the water flosser;

FIG. 6 is a second perspective view of FIG. 5;

FIG. 7 is a third perspective view of FIG. 5;

FIG. 8 is a fourth perspective view of FIG. 5;

FIG. 9 is a first perspective view of a third component of the water flosser;

FIG. 10 is a second perspective view of FIG. 9;

FIG. 11 is a third perspective view of FIG. 9;

FIG. 12 is a fourth perspective view of FIG. 9;

FIG. 13 is a first perspective view of the water flosser showing the first component, the second component and the third component assembled together;

FIG. 14 is a second perspective view of FIG. 13;

FIG. 15 is a third perspective view of FIG. 13; and,

FIG. 16 is a fourth perspective view of FIG. 13.

1 Claim, 14 Drawing Sheets
